DESIGN FOR A TEXTILE FABRIC

Louis Bondy, Baltimore, Md.

Application August 30, 1939, Serial No. 86,937

Term of patent 3½ years

To all whom it may concern:

Be it known that I, Louis Bondy, a citizen of the United States and resident of Baltimore, in the county of Baltimore and State of Maryland, have invented a new, original, and ornamental Design for Textile Fabric, of which the following is a specification, reference being had to the accompanying drawings, forming a part thereof.

Fig. 1 is a plan view of a textile fabric showing my design;

Fig. 2 is a detailed view of the fabric shown in Fig. 1; and

Fig. 3 is an enlarged view of a section of the fabric shown in Fig. 1.

The design consists of loosely twisted wool yarn interspersed with nubs, the warp being of two colors and the filling being of one color.

I claim:

The ornamental design for a textile fabric, as shown and described.

LOUIS BONDY.
